UNITED STATES PATENT OFFICE.

ROSE A. GRAY, OF BELOIT, KANSAS.

SAFETY MAILING-CASE.

1,314,869.

Specification of Letters Patent.

Patented Sept. 2, 1919.

Application filed November 25, 1918. Serial No. 264,025.

To all whom it may concern:

Be it known that I, ROSE A. GRAY, a citizen of the United States, residing at Beloit, in the county of Mitchell and State of Kansas, have invented certain new and useful Improvements in Safety Mailing-Cases, of which the following is a specification, reference being had to the accompanying drawings.

10 This invention relates to mailing cases or cartons, and particularly to a case designed to contain pictures, drawings, paintings or the like objects for shipment by mail.

15 The general object of the invention is to provide a case of this character so designed that drawings or the like will not be creased, folded or otherwise damaged in sending them through the mail, the case being so designed, however, that the drawings are 20 not required to be rolled.

25 A further object is to provide a case of this character made from a one piece blank, if necessary, and another object is to provide a case of this character with a brace which may be shifted in order to permit the introduction of the drawing or other article into the case but when in place prevents the two sides of the case from being collapsed or crushed.

30 Other objects will appear in the course of the following description.

My invention is illustrated in the accompanying drawings, wherein:—

Figure 1 is a face view of a blank for a 35 mailing case constructed in accordance with my invention;

Fig. 2 is a longitudinal sectional view of the mailing case closed.

Fig. 3 is a fragmentary transverse sectional view on the line 3—3 of Fig. 2 looking 40 in the direction of the arrows.

Referring to these drawings, and particularly to Fig. 1, it will be seen that my improved case may be made of one sheet of 45 heavy cardboard or other material, formed to provide the two sides 10 and 11 and the back 12. In other words, the sides 10 and 11 may be compared to the boards of a book and the back 12 with the back of the book.

50 The blank is creased, scored or otherwise formed at 13 to, in a measure, hinge, the sides 10 and 11 to the back. The side 10 is formed at its ends with the flaps 14, which are preferably wider adjacent the back 12.

55 These parts 10, 11 and 12 are all preferably extra thick or reinforced. The free margin

of the side 10 is also scored and slit to provide the flange 15 and the angularly turned tabs 16.

When the ends 14 and the portion 15 are 60 turned up at right angles to the portion 10, the tabs 16 are bent at right angles to the portion 15 and attached to the ends 14 as by paper fasteners. The side 11 is also formed with ends 14^a adapted to be turned 65 up at right angles to the plane of the portion 11 and attached to and formed as part of the portion 11 is the flap 17 which is jointed to the part 11 by a portion 18 corresponding in width to the width of the portion 15 and scored at its junction with the part 11 and with the part 17. Preferably the end flaps 14 and 14^a are formed with registering apertures 19 whereby when the parts 10 and 11 are disposed in confronting 70 75 relation attaching means may be disposed through the perforations so as to hold the parts 10 and 11 in proper closed position. The side 10 is also provided with an aperture through which a paper fastener 20 is 80 placed so as to engage through an aperture 21 in the flap 17.

Extending transversely between the end flaps 14 is a roller 22 which is made of wood or other like material and is fastened in 85 place by tacks, screws or other fastening devices 23 passing through the flaps 14 and into the ends of the roller. This roller is disposed adjacent the widest portions of the flaps 14 and the middle of the roller is 90 grooved as at 24. Disposed within this groove 24 is a metallic clip 25 having two arms U-shaped in cross section, spaced from each other and embraced and connected by these arms to this metallic clip is a brace 26 95 which may be made of wood, metal or heavy cardboard and which has more or less the same shape as the end portions 14 but is not quite so deep. This brace 26 may be rotated upon the roller 22. Any number 100 of these braces may be used.

Preferably the end members 14 and the flange 15 will be reinforced upon their inside or outside faces by pasting thereon relatively heavy strips of cardboard so as to 105 render these ends thoroughly strong and resistive to crushing force when the case is folded into shape. I have not illustrated this reinforcement as it is obvious. Furthermore, while I have illustrated the blank 110 shown in Fig. 1, as being made of one piece of material, it is obvious that it might be

made of a plurality of pieces of material connected to each other by cloth hinges at the points where the blank is illustrated as scored. Preferably also the roller 23 will 5 be covered with canton-flannel 27, with the nap outward so that the roller will not tend to damage or tear any picture or other article which may be disposed within the case. Preferably also the upper and lower edges 10 of the brace 26 will also be covered with canton-flannel 27.

In the use of this device, a picture or other article which is desired to be shipped in it is slipped beneath the roller and transverse 15 brace 26 and then curved around the roller and over upon itself so that the brace 26 is disposed between the two parallel portions of the picture or other object. Then the cover or side 11 is folded over upon the 20 side 10 and the fastening devices are engaged through the perforations 19 and the paper fastener 20 is engaged through the opening 21 and the article is ready for shipment. It will be seen that this device permits 25 pictures of the most delicate character to be transmitted in the mail, without danger of damage, because the picture is not folded. It is simply curved around the roller without creasing the picture and the 30 roller and the brace will prevent the sides being collapsed or crushed upon each other and thus prevent any creasing of the picture. It will be noted that the reason for rotatably mounting the brace 26 upon the roller 22 is 35 to permit this brace to be turned up into a position allowing the article to be inserted beneath the roller without trouble.

While this case is particularly designed 40 for the shipment of fine drawings, etchings, prints and the like, it will be understood that it may be used for the shipment of a variety of other articles, and that I do not wish to be limited to the details of construction as illustrated.

45 It will be understood that a greater number of paper fasteners might be used in the end walls 14 and 14^a in order to hold these end walls locked to each other when the case is closed, the number of these fastening devices being dependent upon the material of which the case is made or the use to which the case is put. It is obvious that the case may be made of various sizes and thickness of material. The brace or braces 26 are to 50 have a width sufficient to permit the article, such as a map, picture or the like to be disposed between the edges of the brace or braces 26 and the case without mashing, indenting, or otherwise damaging the article 55 60 so put in place.

It is also obvious that the article, if in the form of a map or relatively long strip,

may be readily wrapped a plurality of times around the roller 25 and the rounded ends of the braces. The article may be readily 65 inserted in this case by simply opening the case out flat and laying the flaps 15, 17 and 18 out flat, and then the article may be readily slipped beneath the roller and curved over so as to lie against the opposite edge 70 faces of the brace or braces 26 so the article may be wrapped around the roller and the edge faces of the braces a number of times, after which the blank may be folded up in 75 its complete form.

I claim:—

1. A mailing case having a back and two sides foldably connected with the back and having end portions foldably connected to each of the sides, a flanged portion connected to the edge of one of the sides, and a flap connected to the edge of the other side, means for holding the parts with the two sides in confronting relation to each other, a roller extending between and attached to 80 two of the end portions adjacent the back, and a brace rotatively connected to the roller and adapted to extend between the sides parallel to the end portions thereof.

2. A mailing case of the character described having two sides, a back and end portions, a roller attached to the end portions adjacent the back and over which an article is adapted to be bent, and a brace extending at right angles to the axis of the 90 roller and rotatably connected thereto, and extending parallel to the end portions of the case.

3. A mailing case of the character described having two sides, a back and end portions, a roller attached to the end portions adjacent the back and over which an article is adapted to be bent, and a brace extending at right angles to the axis of the 100 roller and rotatably connected thereto and extending parallel to the end portions of the case, the roller being formed with a groove and the brace being connected to said roller by a curved metallic clip disposed in 105 said groove.

4. A mailing case of the character described having two sides and a back, a roller attached to the mailing case adjacent the back and over which an article is adapted to be bent, and a brace extending at right angles to the axis of the roller and rotatably connected thereto and extending parallel to 115 the end edges of said sides.

In testimony whereof I hereunto affix my signature in the presence of two witnesses.
